UNITED STATES PATENT OFFICE.

ARTHUR ODEWAHN AND FREDERICK REICHART, OF LOUISVILLE,
KENTUCKY.

WELL-DIGGER.

SPECIFICATION forming part of Letters Patent No. 521,175, dated June 12, 1894.

Application filed June 21, 1893. Serial No. 478,366. (No model.)

To all whom it may concern:

Be it known that we, ARTHUR ODEWAHN and FREDERICK REICHART, of Louisville, in the county of Jefferson and State of Kentucky, have invented new and useful Improvements in Well-Diggers, of which the following, taken in connection with the accompanying drawings, is a full, clear, and exact description.

10 This invention relates to boring devices or tools especially designed for use under the surface of water, and consists in certain peculiarities hereinafter more fully pointed out and specifically set forth in the claims.

15 In the annexed drawings similar letters of reference denote corresponding parts in all views, in which—

Figure 1 is an elevation of the device with the outer shell raised a sufficient degree above the boring and cutting auger to show clearly the detail arrangement of the latter. Fig. 2 is a similar view turned partly around, showing—as in Fig. 1—one of the flap valves raised above its normal position as in the act 25 of boring into the soft earth under water and Fig. 3 is a bottom end view of the device.

Attached to a central standard —A—, is a pair of rigid blades —b— which have on their free edges a sharp cutting edge suitable 30 for use in cutting into the earth, and hinged to such fixed blades is a pair of flap valves —c—. There are two boring points —F— secured below the rigid cutting blades —c— which points are so arranged below 35 the blades —c— so as to cut into the earth in advance of such blades and loosen the earth so that said blades will easily cut under such loosened and softened earth and cause it to pass within the shell —B—, which is set at 40 its lowest point during the operation of the device.

It will be seen that there are pins —a'— on the lower edge of the shell —B—, projecting below such shell and entering the holes 45 —a— cut in the rigid portions —b— of the auger, said pins —a'— being in the necessary positions to register with such holes and hold the shell —B— securely in position while it is being revolved in the process 50 of boring. The flap-valves —c— are hinged at their edges to the rigid portions —b—

leaving one side of each valve free to rise when pressure is brought to bear from below, the hinges —d— being on the inner side of the device so as to present as little resistance as possible in turning the device in the soil which is being cut into, and in practice the turning of the whole device results in filling the outer shell —B— with the earth and such stones as will enter the space left open 60 when the valves —c— are lifted, the pins —a'— resting meantime in the holes —a— and causing the shell —B— to move with the augers. This is continued until the shell —B— is filled, whereupon the whole device 65 is lifted from the well or other hole being bored, the pin —g— drawn from its engagement with the standard —A— and collar D, which is integrally united with the shell B by the arched arms C and the shell is raised 70 so as to permit dumping the contents of the shell —B—.

The pin —g— is attached, preferably, to a short chain of suitable length one end of such chain being connected securely to the standard —A—, and the standard —A— is provided with a slot at a convenient point above the boring tool, so that when said shell —B— is at its lowest position the pin —g— may be inserted in the slot —e— in the collar —D— 75 and into the said slot in the standard —A—, thus assisting the pins —a'— to hold the shell —B— in position during revolution of the device.

It will be observed that by employing the 85 pin —g— and the slots in the collar and standard for the upper connection upon the raised arms C, and the pins —a'— engaging the holes —a— for the lower connection, the shell —B— is firmly secured in position against the rotation of the 90 auger at such points that practically no obstruction is offered by such combination to the movement of the earth in the shell as the auger is rotated and the shell is filled. These features constitute an important improvement, and great advantages are thereby secured, because by our construction it is not necessary to make the standard A of square or angular cross-section, which configuration is more expensive in fitting, nor is it necessary to provide cross braces running from the 95 central standard to the side of the shell, 100

which offer great obstruction to the free movement of the earth in the shell, especially when the latter is almost filled and thus greatly augment the labor required to work the auger. At the same time our construction greatly facilitates the raising of the shell for dumping the earth, since the only connection which has to be unloosed for that purpose is that of the pin *g* in the slots *e*, very conveniently placed for the purpose and free from contact with the earth in the shell; while the other securing means, the engagement of the pins *a'* in the holes *a*, are disengaged automatically, when the shell is lifted.

15 We are aware that it is not broadly new to provide means for locking the outer edges of the cutting blades direct to the lower edges of the shell to prevent lateral movement, but we are the first, so far as we are aware, to confine such locking means entirely within the periphery of the shell. As already stated, our invention is more particularly devised for boring under water and at considerable depth, and because the resistance at great 25 depths is considerable, we have found it to be of the utmost importance to confine the locking devices and indeed all the parts of the auger within the periphery of the shell, because any projection beyond the periphery 30 must be forced round, as the boring progresses, against the lateral resistance of the earth outside the shell. Such resistance is much greater than the resistance met by the cutting blades, because of the pressure of the 35 superincumbent earth around the shell, and the consequent density of the earth to be cut, and the waste of energy in overcoming such resistance is, in deep borings, very great. We have therefore devised an auger in which 40 such locking device is entirely within the periphery of the shell, and we consider this improvement to be of great importance.

Having the flap valves —*c*— hinged as shown permits the device to be rigidly connected in its several parts, and while so connected it may be revolved in the earth under

the water, the loosened earth passing into the interior of the shell —*B*—, and there remaining and accumulating with each revolution of the whole device until it is filled to its capacity when it is to be raised and dumped as set forth. The tendency during revolution will be to lift the flap valves, but when the device is being raised the weight of the contents of the shell —*B*— will be sufficient to close the flap-valves and hold them in position so as to preclude the escape of any of the contents of such shell —*B*—.

Having described the invention, what we claim as new, and desire to secure by Letters Patent, is—

1. In an earth auger, the combination of a vertical standard, a cutting blade secured to the lower end of said standard, a shell or bucket sliding on said standard above said blade, a locking device at the upper connection of said shell and standard which locks the same against vertical movement thereon, and a locking device locking the lower edge of said shell directly to the outer edge of said blade against lateral movement only, such locking device being comprised within the periphery of the shell substantially as described.

2. In an earth auger, the combination of a vertical standard a pair of cutting blades secured to the lower end of said standard, said blades being perforated near their outer edge, a shell or bucket sliding on said standard, and pins, projecting downward from the shell, to the inner side of which they are secured near its lower edge, adapted to pass through the perforations of the blades, to hold the shell against backward pressure, substantially as described.

In testimony whereof we have hereunto set our hands this 15th day of February, 1893.

ARTHUR ODEWAHN.
FREDERICK REICHART.
